UNITED STATES PATENT OFFICE.

CHARLES L. ELLIS, OF SAN FRANCISCO, CALIFORNIA.

EDUCATIONAL CABINET

SPECIFICATION forming part of Letters Patent No. 498,636, dated May 30, 1893.

Application filed January 12, 1893. Serial No. 458,170. (No model.)

To all whom it may concern:

Be it known that I, CHARLES L. ELLIS, a citizen of the United States, residing in the city and county of San Francisco, State of California, have invented an Improvement in Educational Cabinets; and I hereby declare the following to be a full, clear, and exact description of the same.

My invention relates to that class of educational apparatus in which a traveling strip of paper is confined within a casing and is viewed through a sight aperture.

My invention consists in the novel construction of the casing or cabinet, the arrangement of the paper therein and other details, all of which I shall hereinafter fully describe and shall specifically point out in the claims.

The objects of my invention are, by the novel arrangement of the paper and the disposition of its supporting and guiding parts, to present a perfectly smooth unwrinkled surface, to prevent the sagging of said paper, and to hold it close up to the sight aperture, to confine the paper roll closely and guide it accurately in unrolling, and generally to so simplify the device that its construction shall be practical and economical.

Referring to the accompanying drawings for a more complete explanation of my invention,—Figure 1 is a longitudinal vertical section of my educational cabinet on the line $x-x$ of Fig. 2. Fig. 2 is a vertical cross section on the line $y-y$ of Fig. 1. Fig. 3 is an end view of the inner box section. Fig. 4 is a top view of the outer box section.

The box is a telescopic one composed of the outer section D and the inner section E. The outer section has its top cut out forming a sight aperture in which is a glass G. Extending between the ends of the inner section and notched into the tops thereof, as shown in Figs. 1 and 3, is a top partition C. Upon this lies a plate B, which is preferably a smooth sheet of stiff paste-board. One side b of this bends down over one edge of partition C and extends down into the inner box section a short distance, thus forming, as shown in Fig. 2, a passage b' between said side and the side of the inner box section. The other side b' of this plate B bends over the other edge of partition C, and extends down diagonally to the lower opposite corner or angle of the in-

ner box section, thus forming in said section, as shown in Fig. 2, the two compartments e and e' . The corners where the plate bends over the partition are preferably rounded, as shown, in order to present a smooth surface for the passage of the paper, and the top of said plate is smooth to smoothly direct and support the paper traveling over it. In compartment e' of the inner box section is confined a roll J of paper, loosely placed therein, but sufficiently confined to insure its accurate unrolling. In compartment e is a longitudinal shaft F journaled at one end upon a handled pin I, and at the other end upon a bearing screw or pin H. The end of the paper roll, lettered A, is carried up through passage b' , over the top of plate B, immediately under the sight glass G, and thence down to the winding shaft F, its direction of travel being indicated by the arrows in Fig. 2. Upon the paper is printed any suitable matter of instruction. By winding shaft F, the paper is unrolled from roll J and is wound up on the shaft, passing in its course under the sight aperture.

The points of advantage growing out of the construction and arrangement of parts shown and described may be briefly stated as follows: By the division of the box into compartments, I provide for the reception of a free paper roll without the presence of a separate shaft upon which to mount it and from which to unwind it. I thus dispense with the several shafts usually found in devices of this class, using but one shaft, namely, winding shaft F, while at the same time the paper roll is sufficiently confined, guided and directed to insure its accurate unrolling. This materially simplifies and cheapens the construction. By the employment of the bent plate B, I form the compartments in the simplest manner, and at the same time provide for the accurate direction of the paper, its position close up under the sight glass and its smooth unwrinkled surface thereunder, the rounded corners of said plate making the passage of the paper easy and free from the disadvantage of undue wear and tear.

Having thus described my invention, what I claim as new, and desire to secure by Letters Patent, is—

1. An educational cabinet consisting of a

box having a sight aperture in its top and divided longitudinally into compartments having a top communication, a top support within the upper portion of the box under its sight aperture, a free roll of paper lying in one of the compartments to rotate about an unfixed axis and having its end passing over the top support into the other compartment, and a winding shaft in said compartment upon which the paper is wound, substantially as herein described.

2. An educational cabinet consisting of a box having a sight aperture in its top, a plate extending horizontally under the sight aperture, the sides of said plate being bent downwardly into the box and forming two longitudinal communicating compartments therein, the free paper roll lying in one of said compartments to rotate about an unfixed axis and having its end passing upwardly and over the top of the plate and down into the other compartment, and a winding shaft in said other compartment to which the end of the paper is attached, substantially as herein described.

3. An educational cabinet consisting of a box having a sight aperture in its top, a longitudinal partition in the upper portion of said box, a plate supported upon said partition under the sight aperture, said plate having its sides bent downwardly into the box

and forming two longitudinal communicating compartments therein, the free paper roll lying in one of said compartments to rotate about an unfixed axis and having its end 35 passing upwardly and over the top of the plate and down into the other compartment, and a winding shaft in said other compartment to which the end of the paper is attached, substantially as herein described. 40

4. An educational cabinet consisting of a box formed of sections, the outer section having a sight aperture in its top, the top partition C supported by the ends of the inner section, the plate B lying upon the partition under the sight aperture, and having its sides bent downwardly into the inner box section and dividing it into two longitudinal communicating compartments, the free paper roll lying in one of said compartments and having 45 its end passing upwardly and over the top of the plate and down into the other compartment, and a winding shaft in said other compartment to which the end of the paper is attached, substantially as herein described. 50

In witness whereof I have hereunto set my hand.

CHARLES L. ELLIS.
